(57) **CLAIM**

The ornamental design for a surveillance camera, as shown and described.

DESCRIPTION

1. Surveillance camera

1.1 : Perspective

1.2 : Perspective

1.3 : Front

1.4 : Back

1.5 : Left

1.6 : Top

1.7 : Bottom

1.8 : Right

1.9 : Enlarged

1. Design point of this design product: The shape of the design; 2. The dash-dash broken lines in the drawings depict the portions of the surveillance camera which form no part of the claimed design; 3. FIG. 1.9 is an enlarged view of a portion labeled “1.9” in FIG. 1.1; The dot-dash lines illustrate the boundary of the enlarged portion view of 1.9 in views 1.1 and 1.9 and form no part of the claimed design.

1 Claim, 9 Drawing Sheets
